MONEY WRAPPING DEVICE

Ernest Fortier, Three Rivers, Quebec, Canada

Application September 26, 1947, Serial No. 776,242

1 Claim. (Cl. 93—2)

1 The invention relates to improvements in a money wrapping device, as described in the present specification and illustrated in the accompanying drawings that form a part of the same.

The invention consists essentially of the novel features of construction as pointed out broadly and specifically in the claims for novelty following a description containing an explanation in detail of an acceptable form of the invention.

The objects of the invention are to devise a money wrapping device which will permit the blind to stack and wrap a predetermined number of coins; to furnish a device in which a coin wrapper may be inserted and held in a suitable position to facilitate wrapping money therein; to eliminate the counting of coins by providing a gauge which may be set to determine an exact number of the same; to furnish a money wrapping device which will be simple in construction and inexpensive to manufacture; to offer a money wrapping device which will be easy and simple to use; and generally to provide a money wrapping device which will be durable and efficient for its purpose.

In the drawings:

Figure 1 is a perspective view of the device showing a coin wrapper in position thereon.

Figure 2 is a plan view of the device.

Figure 3 is a sectional view as taken on the line 3—3 in Figure 2.

Figure 4 is a sectional view as taken on the line 4—4 in Figure 2.

Figure 5 is a rear or side view of Figure 2.

Figure 6 is a side view of the sliding holder for the coin rack.

Figure 7 is an end view of Figure 6.

Like numerals of reference indicate corresponding parts in the various figures.

Referring to the drawings, the money wrapping device consists of the coin rack as indicated by the numeral 10 which has the sliding holder 11 suitably mounted therein.

The coin rack 10 consists of the guide plate 12 which is formed from a single sheet of metal or other suitable material. This guide plate has the lugs 13 and 14 formed on the upper outer edges of same towards the front thereof. The rear portion of the guide plate 12 is formed upward in an arcuate manner and the central portion 15 is suitably cut-away thus forming a pair of arcuately shaped walls or backs 16 and 17.

The channel member or slide support 18 is provided with the lugs 19 which are adapted to engage in corresponding slots in the guide plate 12. These lugs 19 are flattened down flush with

the upper surface of the guide plate 12 thus providing a means of securing the channel member 18 substantially on the underside thereof.

The clamping strip or band 20 is of an arcuate shape and forms an integral part of the guide plate 12. This clamping strip in co-operation with the arcuately shaped back 16 is adapted to hold the handle 21 firmly in position on the guide plate 12.

10 The shank or stationary end holder 22 which is integral with the handle 21 and is smaller than the adjacent portion thereof thus providing a suitable space between the same and the arcuately shaped back 16.

15 The sliding holder 11 consists of the sliding holder support or guide strip 24 which is flanged upward at one end thereof and adapted to have the movable end holder 25 fixedly secured thereto. This movable end holder 25 is diametrical in shape and the size of same coincides with that of the stationary end holder 22 of the handle 21.

20 The sliding holder support 24 is rounded on the straight end thereof and adapted to slide into the channel member 18 until the flange on the former strikes the end of the guide plate 12. The channel member 18 projects slightly outward past the end of the guide plate 12 so as to facilitate starting the sliding holder support 24 therewith; while the inner end of this channel member is recessed so as to facilitate pushing the straight end of the sliding holder support 24 outward, thus partially removing same from within the channel member.

25 In the use of the invention a money wrapper 26 is slid under the lugs 13 and 14 on the guide plate 12 and drawn backward. The rear end of the wrapper follows the curvature of the arcuately shaped backs 16 and 17 and is drawn upward and partially around the stationary end holder and movable end holders 22 and 25. The inner faces of these stationary and movable end holders are a predetermined distance apart so as to permit the correct number of coins to be stacked or placed in an orderly arrangement therebetween. After stacking the coins the money wrapper 26 is drawn upward and around the stationary and movable end holders 22 and 25 and the stack of coins. From this point the wrapper 26 is rolled around the coins and is guided by the stationary and movable end holders until the paper is completely rolled around the same. The coin rack 10 is suitably tilted and the movable end holder 25 on the sliding holder 11 is then slidably removed from the guide plate 12. This end of the wrapper is then folded in on the coins and

the wrapper and coins are then removed from the coin rack so that the opposite end of the wrapper may be folded in on the same.

What I claim is:

In a money wrapping device, a guide plate, lugs on said guide plate, arcuately shaped walls extending upward from the rear portion of said guide plate and being integral therewith, a channel member fixedly secured on the under side of said guide plate, a sliding holder supported in said channel member, a movable end holder secured on said sliding holder and extending over one edge of said guide plate, a handle secured on said guide plate, a shank extending inward from said handle, said shank and said movable end holder being suitably spaced apart and in alignment with respect to one another, said guide plate holding a money wrapper suitably held in position thereon by said lugs and adapted to be inserted between said arcuately shaped walls and said movable end holder and said shank, a portion of the money wrapper following the contour of said arcuately shaped walls thus facilitating the jux-

taposition and rolling of coins therein, and said movable end holder being removed from said guide plate thus releasing the money wrapper and the coins therein and permitting the money wrapper to be folded in on each end thereof.

ERNEST FORTIER.
